FRIED. KRUPP AKTIENGESELLSCHAFT, OF ESSEN-ON-THE-RUHR, GERMANY

POINTING DEVICE FOR ORDNANCE.

1,384,000.

Specification of Letters Patent.

Patented July 5, 1921.

Application filed September 7, 1920. Serial No. 408,746.

To all whom it may concern:

Be it known that we, RICHARD SCHÜRMANN, residing at Essen, Germany, and LEOPOLD SCHMIDT, residing at Essen, Germany, both citizens of the German Republic, have invented a certain new and useful Improvement in Pointing Devices for Ordnance, for which we have filed application in Germany, filed Jan. 18, 1918, of which the following is a specification.

This invention relates to pointing devices for guns, two members of which are rotatable about similarly directed axes and adjustable parallel to each other. In known pointing devices of this kind there is provided on one of the two parts of the gun an arm provided with an adjusting mark, which latter can be set to a mark arranged on the other part of the gun. These known pointing devices suffer from the disadvantage that an arm of great length must be provided in order to obtain an adequately accurate adjustment.

This invention refers to a pointing device of the kind hereinbefore mentioned, in which this disadvantage is avoided without prejudice to the accuracy of the adjustment obtainable.

This invention will be described with reference to the accompanying drawings which show a pointing device for adjusting the elevation of the gun barrel and which is constructed according to this invention.

Figure 1 is a side elevation of the pointing device itself together with the adjacent parts of the gun.

Fig. 2 is a section on the line 2-2 of Fig. 1, on an enlarged scale looking from the right, and

Fig. 3 is a section on the line 3-3 of Fig. 1, looking from the right.

A denotes the gun barrel which moves longitudinally when the gun is fired in a cradle B, which is pivotally mounted by means of two trunnions b' in the gun carriage C and can be adjusted together with the gun barrel A by means of toothed sector elevating gear B² (see Fig. 1). On one of the two trunnions b' is mounted a rocking lever D adapted to rotate independently thereof and which is coupled by two parallel connecting rods E to a second rocking lever F adapted to rotate about a similarly directed axis. This rocking lever F is rigidly attached to a shaft F' which is carried

in a sleeve c' mounted on the gun carriage, which bearing sleeve c' is enlarged at its free end into a drum shaped hollow journal c², on which is rotatably mounted a sleeve G closed at its end by a cover plate g'.

In the sleeve G, which carries a sighting telescope G², is mounted a worm H, which is selflocking and can be adjusted by means of a small milled head h' and engages with a series of teeth c³ on the hollow journal c² so that the sleeve G can therefore be so rotated relatively to the stationary hollow journal c² by turning the milled head h' that the sighting line of the sighting telescope G² receives the direction corresponding to the elevation of the target. There is also mounted in the sleeve G a second worm J, which can be adjusted by means of a milled head i' and which projects into an opening c⁴ in the hollow journal c² and is in engagement without a toothed sector rigidly connected to the shaft F'.

Let it be supposed that there is a shaft f-f' at right angles to the axis of rotation of the shaft F' and the shaft is so adjusted that the angle which the axis f-f' forms with the sighting line of the sighting telescope G² is equal to the angle of the attachment corresponding to a fixed distance away of the target, when each such adjustment corresponds within certain limits with a fixed distance away of the target. The ranges of the target are read off by means of a graduation f⁴ (see Fig. 1), which is arranged on a sector shaped disk F³ rigidly connected to the shaft F', and a mark g⁴ (Fig. 1) which is situated on the edge of an opening g³ provided in the cover plate g'.

Underneath the trunnion b', which carries a rocking lever D is mounted, in a sleeve c⁵ attached to the gun carriage C, a shaft K provided with a spur wheel gearing k' (see Fig. 2). The spur pinion k' gears with a toothed sector D' (see Fig. 2) which is rigidly connected to the rock lever D.

On the shaft K is mounted a pinion M, which is adapted to rotate independently thereof and is in engagement with a toothed sector B³ rigidly connected to the trunnion b'. The ratio of transmission of the teeth B³ is equal to ratio of transmission of the teeth D' k and is so proportioned that the spur pinion M positively connected to the gun barrel has to make more than one revolution when the gun barrel turns from one

limit to the other of the range of elevation. To the spur pinion M is rigidly connected a disk M' and to the shaft K a disk K^2 bearing against the disk M' , which disk K^2 has an adjustment mark h^4 , which is arranged on a slide K^3 guided in a radial direction on the disk K^2 . The slide K^3 engages by means of a pin h^5 in a spiral groove m^2 in the disk M' , so that on mutual rotation of the disks M' and K^2 the slide K^3 is moved in a radial direction relatively to the disk K^2 . The adjustment mark h^4 adjustably mounted on the disk K^2 is corresponded to on the disk M' by a stationary adjustment mark m^3 situated opposite it. Assume the two parts A and F' of the gun which are adjustable independently of each other, to be adjusted that shaft $f-f$ supposed to be fixed to the shaft F' is parallel in any desired angular position as regards the gun carriage C with the longitudinal axis of the gun barrel A , this mutual position of the parts A and F' of the gun is corresponded to by a certain mutual angular position of the disks K^2 and M' , since the disk K^2 is positively connected to the shaft F' and the disk M' to the gun barrel A . Assume also that the axis $f-f$ is rotated into a different angular position relatively to the gun carriage and the gun barrel is simultaneously so adjusted that the longitudinal axis is again parallel with the axis $f-f$ then, in this latter case the disks K^2 and M' will be rotated through equal angles, since the ratio of transmission between the disk K^2 and the shaft F' is equal to the ratio of transmission between the disk M' and the gun barrel. The disks K^2 and M' possess therefore after this adjustment exactly the same mutual angular position as they did previously. It follows from this that the mark h^4 , if the longitudinal axis and the axis $f-f$ are set parallel with each other, always points to the same point on the disk M' . This point is rendered recognizable by the adjustment mark m^3 . If therefore the mark h^4 of the adjusting member formed by the disk K^2 points to the point on the adjusting member formed by the disk M' indicated by the mark m^3 , then the longitudinal axis is always parallel with the axis $f-f$ that is to say, the two parts A and F' of the gun are set parallel with each other.

55 The use of the above described pointing device takes place in the following way. By turning the milled head h' the sleeve G is first so rotated by means of the worm wheel gearing H , c^2 on the stationary hollow journal c^2 that the sighting line of the sighting telescope G^2 receives the direction corresponding to the elevation of the the target. Next by turning the milled head i' the shaft F' is so adjusted by means of the worm wheel gearing J , F^2 , that the graduation

mark of the graduation f^4 , which corresponds to the range of the target is brought opposite the reading off mark g^4 on the edge the opening g^3 (see Fig. 1). The axis $f-f$ then makes with the sighting line an angle, which is equal to the firing angle corresponding to the range of the target. The rotation which the shaft F' makes during the said adjustment, is transmitted by the rocking lever F and the connecting rods E connected thereto to the rocking lever D and to the toothed sector D' rigidly attached thereto so that the toothed sector D' sets the shaft K together with the disk K^2 attached thereto in rotation by means of the spur pinion h' (see Fig. 2). Under these circumstances the disk K^2 is as a rule brought into an angular position with respect to the disk M' in which the mark h^4 lines in a different axial plane to the mark m^3 . At the same time the slide K^3 which carries the mark h^4 is moved owing to the engagement of the pin h^5 in the spiral groove m^2 a certain distance in a radial direction. The desired elevation is now imparted to the gun barrel by means of the elevating gear while the disk K^2 remains at rest. The rotation of the gun barrel which takes place here, is also taken up by the toothed sector B^3 which is rigidly attached to one of the trunnions and the rotation of this toothed sector is transmitted by the spur pinion M to the disk M' . In consequence of the rotation of the disk M' relatively to the stationary disk K^2 , the slide K^3 , which carries the mark h^4 is again moved in a radial direction over the disk M' in consequence of the engagement of the pin h^5 in the spiral groove m^2 . As soon as the disk M' has been moved such an amount that on the one hand the mark m^3 lies in the same axial plane as the mark h^4 and on the other hand the slide K^3 has been moved such a distance in a radial direction that the mark h^4 points to the point on the disk M' indicated by the mark m^3 , the longitudinal axis of the gun barrel is parallel with the axis $f-f$ that is to say, the sighting line of the telescope G^2 also forms with the longitudinal axis of the gun barrel an angle which is equal to the firing angle which corresponds to the range of the target. The desired elevation has therefore been imparted to the gun barrel.

55 As the disk M' can rotate through more than 360° relatively to the disk K^2 when the gun barrel is adjusted the possibility exists that at a certain adjustment of the gun barrel the marks m^3 and h^4 may lie in the same axial plane but when the longitudinal axis of the gun barrel is not parallel with the axis $f-f$. No error can however arise through this since in this case the radial distance of the mark h^4 from the common axis of rotation of the disks K^2 and M' is differ-

ent from the corresponding distance of the mark m^3 therefrom, so that the mark k^4 can not therefore point to the point indicated by the mark m^3 .

5 Because when the angles of rotation of the gun barrel A and the member F' are the same, the corresponding angles of rotation of the disks M' and K² amount to a multiple of the first mentioned angles of rotation, the 10 result is that in the case of an inaccurate mutual adjustment of the marks k^4 and m^3 the difference between the directions of the longitudinal axis of the gun barrel and the axis f—f can only amount to a small fractional part of the error made in the adjustment of the marks k^4 and m^3 . This error becomes greater under otherwise equal conditions, as the distance of the marks k^4 and m^3 become smaller from the common axis of 15 rotation of the disks K² and M'. As, however, the difference between the directions of the longitudinal axis of the gun barrel and the axis f—f amounts to only a fractional part of this error, it is possible even 20 in the case of a small distance of the marks k^4 and m^3 from the common axis of rotation of the disks K² and M' and accordingly also for a correspondingly small amount of space occupied by the adjusting members K² and 25 M', to obtain a sufficiently accurate adjustment of the gun barrel.

Claims:

1. A pointing device for guns comprising a range device, a pair of adjusting members 35 rotatable independently of each other about the same axis, means connecting said range device to one of said adjusting members, said connecting means moving said adjusting member through a greater angle than the 40 angle of rotation of the range device, means connecting the second adjusting member to the gun, said means moving the second adjusting member through an angle greater than the angle of rotation of the gun part 45 appertaining thereto, the ratio of rotation of said adjusting members being the same, substantially as and for the purpose described.

2. A pointing device of the character described which comprises the combination with a gun and trunnions therefor of a sighting telescope, a range device connected to said telescope, an adjusting member positively connected to said range device and operated thereby, a second adjusting member 55 coöperating with said first adjusting member and positively moved when the gun is elevated, said adjusting members having the same ratio of movement and being constructed to move through an angle greater than the angle of rotation of the range device and gun respectively, said first and second mechanism having a movable and a stationary adjustment mark respectively, as 60 and for the purpose set forth.

3. A pointing device for guns which comprises a range device, two adjusting members, means for positively connecting one of the adjusting members to the range device so that upon a movement of the range device a 70 corresponding movement of the adjusting member will occur, the second adjusting member being positively connected to the gun trunnion in such a manner that movement of the gun will be correspondingly 75 transmitted to this adjusting member, said adjusting members having the same ratio of rotation but moving through a greater angle than the angle of rotation of the range device and gun trunnion respectively, a variably positioned adjustment mark on the first 80 adjusting member and a coöperating adjustment mark upon the second adjusting member, as and for the purpose set forth.

4. A pointing device for guns which comprises a range device, a pair of adjusting members, means positively connecting the range device to the one of the adjusting members, means positively connecting the second adjusting member to the trunnion of 90 the gun in such a manner that a movement of the gun is correspondingly transmitted to the second adjusting member, an adjusting mark permanently fixed with relation to the second adjusting member, another adjustment mark operatively mounted with respect to the first adjusting member, said adjustment mark being variable, the means for varying the position of this mark comprising a slide upon which the mark is 100 placed, a pin projecting from said slide, said pin engaging a spiral groove arranged in the face of the second adjusting member, substantially as and for the purpose set forth.

5. A pointing device for guns which comprises a range device, a pair of adjusting members, a shaft for each adjusting member, said shafts being co-axially arranged, means comprising a pair of rocking levers 110 and a pair of connecting arms for operatively connecting said range device to one of said adjusting members so that a movement of the range device will be correspondingly transmitted to the adjusting member, a segment and pinion mechanism for operatively connecting the second adjustable member to the trunnion of a gun in such a manner that movement of the gun will be correspondingly transmitted to the 115 second adjusting member and coöperating adjustment marks on the said adjusting members, as and for the purpose set forth.

6. A pointing device for adjusting two gun parts rotatable independently of each other about axes of the same direction to assume a particular angular position relatively to each other, said pointing device comprising two adjusting members rotatable 120 independently of each other about the same 130

- axis, a gearing positively connecting each of said adjusting members to one of said gun parts respectively, each gearing having the same ratio of transmission and being constructed to turn the adjusting member connected thereto through an angle greater than the angle of rotation of the gun part appertaining thereto and each of said adjusting members carrying an adjusting mark adapted to register the adjusting mark of the other adjusting member when said gun parts assume their particular angular position relatively to each other.
7. A pointing device for adjusting two gun parts rotatable independently of each other about axes of the same direction to assume a particular position relatively to each other, said pointing device comprising two adjusting members rotatable independently of each other about the same axis, a gearing positively connecting each of said adjusting members to one of said gun parts respectively, each gearing having the same ratio of transmission and being constructed to turn the adjusting member connected thereto through an angle, greater than 360 degrees, a slide mounted on one of said adjusting members and movable in radial direction, said slide and said other adjusting member carrying adjusting marks adapted to register each other, means for altering the radial distance between said adjusting marks, said means being adapted to be actuated by the rotation of each of said adjusting members and causing said distance to be altered by the same amount but in opposite direction when said adjusting members are rotated through the same angle and in the same direction.
- 40 8. A pointing device for adjusting two gun parts rotatable independently of each other about axes of the same direction to assume a particular angular position relatively to each other, said pointing device comprising two adjusting members rotatable independently of each other about the same axis, one of said adjusting members carrying an adjusting mark fixed thereto, a slide mounted on the other adjusting member and movable in radial direction, said slide carrying an adjusting mark adapted to register said first-named adjusting mark, a gearing positively connecting each of said adjusting members to one of said gun parts respectively, each gearing having the same ratio of transmission and being constructed to turn the adjusting member connected

thereto through an angle greater than 360 degrees, and a gearing for radially displacing said slide, said gearing being adapted to be actuated by the rotation of each of said adjusting members.

9. A pointing device for adjusting two gun parts rotatable independently of each other about axes of the same direction to assume a particular angular position relatively to each other, said pointing device comprising two adjusting members rotatable independently of each other about the same axis, one of said adjusting members carrying an adjusting mark fixed thereto, a slide mounted on the other adjusting member and movable in radial direction, said slide carrying an adjusting mark adapted to register said first named adjusting mark, a gearing positively connecting each of said adjusting members to one of said gun parts respectively, each gearing having the same ratio of transmission and being constructed to turn the adjusting member connected thereto through an angle greater than 360 degrees, and a pin projecting from said slide, said pin engaging a spiral groove arranged in the face of said first named adjusting member.

10. A sighting device for ordnance comprising a sighting means carrier, a range member rotatable independently of the gun barrel about an axis having the same direction as the axis of the gun trunnions, means for adjusting said range member and the sighting means carrier relatively to each other for range, two adjusting members rotatable independently of each other about the same axis, a gearing positively connecting one of said adjusting members to the gun barrel, another gearing positively connecting the other adjusting member to said range member, each gearing having the same ratio of transmission and being constructed to turn the adjusting member connected thereto through an angle greater than the angle of rotation of the gun-barrel and said range member respectively, and each of said adjusting members carrying an adjusting mark adapted to register the adjusting mark of the other adjusting member when the sighting means carrier and said range member are adjusted relatively to each other for the range of zero and the axis of the bore of the gun barrel is parallel to the sighting line.
